Primary Examiner — Darlington Ly(74) *Attorney, Agent, or Firm* — Raggio & Dinnin, P.C.(57) **CLAIM**

The ornamental design for an oscillating blade, as shown and described.

DESCRIPTION

FIG. 1 is a perspective view of a design for an oscillating blade in accordance with the present invention.

FIG. 2 is a front elevation view of the design for an oscillating blade as shown in FIG. 1.

FIG. 3 is a back elevation view of the design for an oscillating blade as shown in FIG. 1.

FIG. 4 is a side elevation view of the design for an oscillating blade as shown in FIG. 1.

FIG. 5 is a side elevation view of the design for an oscillating blade as shown in FIG. 1.

FIG. 6 is a top view of the design for an oscillating blade as shown in FIG. 1; and,

FIG. 7 is a bottom view of the design for an oscillating blade as shown in FIG. 1.

1 Claim, 5 Drawing Sheets
